UNITED STATES PATENT OFFICE

2,554,127

HYDRAULIC JACK

Fielding B. Simmons, Vallejo, Calif.

Application February 1, 1945, Serial No. 575,705

15 Claims. (Cl. 60—52)

1

My invention relates to hydraulic mechanism, and a particular embodiment thereof in a hydraulic vise;

One of the principal objects of this invention is to provide a hydraulic mechanism having a novel release or equalizing valve, and a novel pump for transferring fluid under pressure to operate the moving element, an important object also being to provide novel cam or unitary means for operating the valve and pump.

Another important object of this invention is to provide a hydraulic mechanism in which the pump for operating the working piston plunger is embodied in the working or operating piston or plunger itself, and also a structure of this class in which the release or equalizing valve is also embodied in the piston.

An important object also of this invention is to provide a vise incorporating the aforementioned feature of the pump in the operating piston or plunger.

A further important object of this invention is to provide a working or operating piston which is moved by fluid under pressure supplied by pump means actuated by the oscillation or operation of the piston rod, and in which such mechanism is embodied in a hydraulic vise, in which the usual operating handle serves to oscillate or operate the piston rod.

Still another important object of this invention is to provide a hydraulic vise in which the movable jaw may be freely moved by the handle when the latter is in a predetermined position.

A still further important object of this invention is to provide a vise in which, at several predetermined positions of the handle, the movable jaw may be readily shifted as desired, and also by pumping or oscillating action of the handle, any desired compressing or clamping force may be obtained between the jaws.

Still another important object of this invention is to provide a vise which may be quickly manipulated and with particular ease and sensitivity.

A still further important object of this invention is to provide novel means for readily varying the maximum pressure or clamping force between the jaws.

With these and other objects in view, as will appear hereinafter, I have devised a hydraulic mechanism having a particularly novel embodiment in a hydraulic vise, as will be hereinafter described in detail and particularly set forth in the appended claims, reference being had to the accompanying drawings, and to the characters

of reference thereon, which form a part of this application, in which:

Fig. 1 is a plan view of my vise, in one form of construction, with the rear portion broken away and in section to facilitate the illustration;

Fig. 2 is a partial elevational and partial longitudinal sectional view of my vise, the section being taken substantially through 2—2 of Fig. 1;

Figs. 3, 4, and 5 are transverse sectional views thereof, taken through 3—3, 4—4, and 5—5 of Fig. 2;

Fig. 6 is a partial front elevation of the vise and also a diagrammatic view showing various operating positions of the piston rod and handle;

Fig. 7 is a fragmentary sectional view similar to the rear end of Fig. 2, but on an enlarged scale, of a slightly modified form of construction;

Fig. 8 is a transverse sectional view thereof, taken through 8—8 of Fig. 7;

Fig. 9 is a transverse sectional view thereof, taken through the same plane of Fig. 7, as in Fig. 8 but showing the piston rod slightly rotated about its axis for closing the release valve;

Fig. 10 is a transverse sectional view thereof, taken through 10—10 of Fig. 7; and

Fig. 11 is a longitudinal sectional view taken through 11—11 of Fig. 8, showing primarily the pressure adjusting or relief valve.

The vise, shown in the drawings, and embodying my invention of the hydraulic means is similar in appearance to other vises now in use. It consists, in its outward appearance, generally of a base 1 having a stationary jaw 2, a movable jaw 3 positioned in opposed relation to the jaw 2, a shank 4^a, of inverted channel construction, extending inwardly from the front wall or apron 4^b of the jaw member 4, the shank being slidably mounted on the base 1, a rod 5 extending backwardly from the front wall or apron 4^b and located primarily within the inverted channel shaped shank 4^a, and a handle 6 secured to the outer end of the rod 5 for rotating the latter and operating the hydraulic mechanism of the device, as will be hereinafter described.

The base 1 is elongated and supports a cylinder 7 which extends longitudinally thereof. The jaw 2 is supported at the front end of a bridged housing 8 which is carried by the base 1 and extends around the forward portion of but is spaced from the cylinder 7. The space between the cylinder 7 and the housing 8 provides a longitudinal passage in which the shank 4^a of the movable jaw member 4 is slidable, the cylinder 7 and the

housing 8 guiding the shank 4^a, holding the jaws 2 and 3 in alignment.

The cylinder 7 has a cylindrical bore 7^a, the forward portion 7^b thereof being referred to as the compression chamber and the rear end portion 7^c being referred to as the reservoir. In the bore of the cylinder is reciprocably mounted a piston 9 which is non-rotatable therein. The rod 5, which may be referred to as the piston rod, is fixedly connected to the piston against a shoulder near the inner end of the rod by a hub of a cam 10, both the rod and the cam being rotatable with respect to the piston. The rod 5 is coaxial with the bore of the cylinder and extends forwardly of the piston and through the forward wall or apron 4^b of the jaw member 4. The rod 5 is axially fixed in the apron 4^b by a shoulder 5^a on the rod and a spacer bushing 11.

In the lower portion of the piston 9 as shown in Fig. 2 is a release or equalizing valve 12 having a valve portion 12^a adapted to be seated over the forward end of the port 9^a which connects the compression chamber 7^b with the reservoir chamber 7^c at respectively the forward and rear ends of the piston. The valve 12 is normally biased to its closed position by a spring 12^b.

At the upper portion of the piston is provided a bore 9^b in the forward end of which is reciprocably mounted a compression valve 13 and in the rear end of which is reciprocably mounted a plunger 14. The piston is also provided with a laterally spaced bore 9^c which is joined at its inner end to the intermediate portion of the bore 9^b. The bore 9^c terminates flush with the rear side of the piston. In the latter end of the bore 9^c is provided an intake valve 15. The valves 13 and 15 are normally biased to their closed positions by springs 13^a and 15^a, respectively.

Outward or rearward movement of the plunger 14 causes the valve 15 to become unseated, drawing a charge of fluid from the reservoir 7^c, and inward or forward movement of the plunger causes compression of the fluid and unseating the valve 13 thereby forcing the charge of compressed fluid into the compression chamber 7^b of the cylinder.

In this manner, the piston 9 is forced inwardly or backwardly, drawing the jaw member 4 inwardly and the jaw 3 toward the jaw 2 for tightly clamping an article between the jaws.

The unseating of the valve 12 and the operation of the pump plunger 14 is effected by the cam 10 which is positioned behind the piston and is provided at the side adjacent the piston with a helical cam surface 10^a. The cam is so positioned that the initial movement thereof, and of the handle 6, as indicated by the arc designated A in Fig. 6, causes unseating of the valve 12. Continuing rotation of the cam permits the valve 12 again to seat, and forces the plunger 14 inwardly in order to force a charge of fluid into the compression chamber 7^b of the cylinder. Oscillation of the handle 6, and therefore of the cam 10, causes continued reciprocation of the plunger 14 and causes continued forcing of fluid, under pressure, into the chamber 7^b, thereby forcing the jaw 3 toward the jaw 2. The arc of oscillation of the handle and the cam is indicated by B in Fig. 6.

In order to regulate or limit the rotative movement of the rod 5, I have provided an arcuate groove 4^c at the backside of the apron or wall 4^b, and I have provided a stop 5^b on the rod 5 which engages the ends of the groove 4^c, thereby limiting the circular movement of the rod. Since

such a stop means is a common expedient, it is not shown in detail.

The pressure in the chamber 7^b is controlled by a regulating screw 21 at the rear end of the base. In the base is provided a longitudinal passage 1^a which connects the forward and rear ends of the cylindrical bore 7^a. At the rear portion of the passage is provided a plunger 22, which, in its forward position, intercepts the passage 1^a and thereby prevents flow of fluid from one chamber of the cylindrical bore to the other. The plunger 22 is held in its forward position by a spring 23, the compression of which is controlled by the regulating screw 21. When the pressure in the chamber 7^b becomes excessive, the fluid therein forces the plunger 22 to compress the spring 23 and allows the fluid to flow into the reservoir chamber 7^c, thus serving as a relief valve for the fluid pressure in the forward compartment or compression chamber.

In the modified form of construction shown in Figs. 7 to 11, inclusive, the primary difference from the structure above described is the location of the operating cam within the piston and the embodiment of the main release valve member within the operating cam. The piston shown in the modified structure is designated 31, the operating cam 32, and the release valve member 33. The piston in this instance is also reciprocably but non-rotatably mounted in the bore 7^a of the cylinder 7. The inner end of the rod 5 is reduced, as indicated by 5^b and this reduced portion is rotatably mounted in the piston. The unit of the cam 32 and the release valve member 33 is non-rotatably secured to the outer end of the rod by a nut 34. Against the forward end of the cam is provided a washer 35 which is positioned against a shoulder on the rod, thus permitting the rod to rotate freely within the piston.

The release valve in this instance consists of a longitudinal port 31^a in the piston and a port 33^a at the peripheral portion of the valve member. When the valve member 33 is in a predetermined position, the port 33^a is aligned with the inner end of the port 31^a, permitting free passage of the operating fluid between the opposite ends of the cylinder or the piston.

At the opposite side of the piston is a bore 31^b which is parallel to the axis of the piston and in the front and rear ends thereof are located compression and intake valves 36 and 37, respectively, these valves being normally biased to their closed positions by springs as described in connection with the foregoing structure.

The cam 32 is a plate cam, against the peripheral surface of which is positioned a plunger 38 which is radially reciprocated within the piston as the rod 5 is rotated, the plunger 38 being normally held against the cam surface by a spring 39. As the plunger is drawn inwardly by the rotation of the cam, a charge of fluid is drawn in from the reservoir, and radially outward movement of the plunger 38 causes compression of the fluid in the bore 31^b and ejection of the compressed fluid through the valve 36 into the compression chamber 7^b of the cylinder.

In this construction also the handle 6, or rod 5, may be oscillated to cause a pumping action in order to force the operating fluid into the compression chamber from the reservoir.

At one side of the piston, intermediate the release valve and the pump is provided another bore 31^c opening into the compression chamber 7^b. This bore 31^c is counter-bored at 31^d and this counter-bore is connected to a large bore 31^e.

by a port 31^c. In the bore 31^c is located the aforementioned cam 32 and valve member 33, the latter tightly but rotatably engaging the wall of the bore 31^c. In the counter-bore 31^d is reciprocably mounted a plunger valve 40 which is held in its seated position against the shoulder, between the bore 31^c and the counter-bore 31^d, by a compression spring 41 which is held under a variable tension therein by a screw plug 42. When the pressure within the compression chamber 7^b becomes excessive, it unseats the plunger 40 and allows the fluid to be forced therefrom through the port 31^c into the bore 31^c, for relieving the pressure in the compression chamber. The valve member 33 is provided with a longitudinal port 33^b for connecting the inner end of the bore 31^c with the reservoir 7^c.

The screw 42 is adjusted when the piston is shifted to its extreme inner or rear position, which occurs when the two jaws 2 and 3 engage each other. When in such inward position, the screw slot in the screw 42 is capable of receiving a screw driver portion 43^a at the inner end of the adjusting screw 43, which extends through the rear wall 7^d of the cylinder. Rotation of the screw 43 adjusts the screw 42.

In both structures, as shown best in Fig. 1, the cylinder 7 is substantially filled with the operating fluid at the rear end by the removal of a plug 44, the forward end of the cylinder being provided with a bleeder line normally closed by a plug 45.

In both structures there is provided at the rear end of the cylinder an air compression chamber 7^e which is normally closed by a plug 46. This air compression chamber is adapted to contain air to allow the expansion of the operating fluid within the reservoir.

Though I have shown and described a particular construction, combination, and arrangement of parts and portions, of my hydraulic mechanism, and a particular embodiment thereof, in a hydraulic vise, and a certain modification thereof, I do not wish to be limited to the same, but desire to include in the scope of my invention the construction, combination, and arrangement substantially as set forth in the appended claims.

I claim:

1. In a means of the class described, a cylinder, a piston reciprocably mounted therein and dividing the cylinder into separate chambers, a release valve for connecting, when open, the chambers of the cylinder at the opposite ends of the piston, pump means in the piston for forcing fluid from one chamber to the other to move the piston, a rod for the piston, said rod being mounted for oscillatory and reciprocable movement in the cylinder, and a cam on the rod for actuating the pump when the rod is oscillated.

2. In a means of the class described, a cylinder, a piston reciprocably mounted therein and dividing the cylinder into separate chambers, a release valve in the piston, pump means in the piston for forcing fluid from one chamber to the other to move the piston, a rod for the piston, said rod being mounted for oscillatory and reciprocable movement in the cylinder, and a cam on the rod for separately actuating the pump and the valve when the rod is oscillated.

3. In a means of the class described, a cylinder, a piston reciprocably mounted therein and dividing the cylinder into separated chambers, a release valve in the piston, pump means in the piston for forcing fluid from one chamber to the other to move the piston, a rod for the piston,

said rod being mounted for oscillatory and reciprocable movement in the cylinder, and cam means on the rod for controlling the valve and for actuating the pump when the rod is oscillated.

4. In a means of the class described, a cylinder, a piston reciprocably mounted therein and dividing the cylinder into separate chambers, a release valve in the piston, pump means in the piston for forcing fluid from one chamber to the other to move the piston, a rod for the piston, said rod being mounted for oscillatory and reciprocable movement in the cylinder, and a helical cam on the rod for controlling the valve and for actuating the pump when the rod is oscillated.

5. In a means of the class described, a cylinder, a piston reciprocably mounted in the cylinder, a rod extending through the front end of the cylinder and connected to the piston, a release valve on said piston for connecting, when open, the chambers of the cylinder at the opposite ends of the piston, pump means on said piston also connecting said chambers for forcing fluid into one of said chambers from the other, and cam means in said cylinder in association with the inner end of the rod for controlling the valve and for actuating the pump.

6. In a means of the class described, a cylinder, a piston reciprocably mounted in the cylinder, a rod extending through the front end of the cylinder and connected to the piston, a release valve on said piston for connecting, when open, the chambers of the cylinder at the opposite ends of the piston, pump means on said piston also connecting said chambers for forcing fluid into one of said chambers from the other, oscillating cam means in said cylinder in association with the inner end of the rod and coaxial therewith for controlling the valve and for actuating the pump, and a pressure control valve on said piston connecting the chambers for controlling the pressure in the chamber into which the fluid is forced by the pump.

7. In a means of the class described, a cylinder, a piston reciprocably mounted in the cylinder, a rod extending through the front end of the cylinder and connected to the piston, a release valve for connecting, when open, the chambers of the cylinder at the opposite ends of the piston, pump means in the piston for forcing fluid from the chamber at one end of the piston to the chamber at the other end to move the piston, said rod being provided at the outer end with means for oscillating the same, and a cam on the rod for actuating the pump when the rod is oscillated.

8. In a means of the class described, a cylinder, a piston reciprocably mounted in the cylinder, a rod extending through the front end of the cylinder and connected to the piston, a release valve in the piston, pump means in the piston for forcing fluid from the chamber at one end of the piston to the chamber at the other end to move the piston, said rod being provided at the outer end with means for rotating the same, and a cam on the rod for actuating the pump.

9. In a means of the class described, a cylinder, a piston reciprocably mounted in the cylinder, a rod extending through the front end of the cylinder and connected to the piston, a release valve in the piston, pump means in the piston for forcing fluid from the chamber at one end of the piston to the chamber at the other

end to move the piston, said rod being provided at the outer end with a means for rotating the same, and a cam on the rod for controlling the valve and for actuating the pump.

10. In a means of the class described, a cylinder, a piston reciprocably mounted in the cylinder, a rod connected to the piston and extending from the cylinder, a release valve in the piston, pump means in the piston for forcing fluid from the chamber at one end of the piston to the chamber at the other end to move the piston, said rod being provided at the outer end with means for rotating the same, a cylinder cam at the inner end of the rod, said cam having a cam surface for unseating the release valve when the cam is in one extreme position, said cam surface having a portion for operating the pump when said rod is oscillated.

11. In a means of the class described, a cylinder, a piston reciprocably mounted in the cylinder, a rod connected to the piston and extending from the cylinder, a release valve in the piston, a pump means in the piston for forcing fluid from the chamber at one end of the piston to the chamber at the other end to move the piston, said rod being provided at the outer end with a means for oscillating the same, a plate cam on the rod within the piston for actuating the pump when the rod is oscillated.

12. In a means of the class described, a cylinder, a piston reciprocably mounted in the cylinder, a rod connected to the piston and extending from the cylinder, a release valve in the piston, pump means in the piston for forcing fluid from the chamber at one end of the piston to the chamber at the other end to move the piston, said rod being provided at the outer end with a means for oscillating the same, a plate cam on the rod within the piston for actuating the pump when the rod is rotated, said release valve being associated with said rod for controlling the valve when the rod is oscillated.

13. In a means of the class described, a cylinder, a piston reciprocably mounted in the cylinder, a rod connected to the piston and extending from the cylinder, a release valve in the piston, pump means in the piston for forcing fluid from the chamber at one end of the piston to the chamber at the other end to move the piston, said pump comprising an intake valve at the rear end of the piston, a compression valve at the forward end of the piston, and a plunger in the piston for drawing fluid through the intake valve and ejecting the fluid through the compression valve into the forward compression chamber, said rod being provided at the outer end with a means for rotating the same, a cylinder cam at the inner end of the rod, said cam having a cam surface for unseating the release valve when the cam is in one extreme position, said cam surface having a portion for

actuating the plunger in the piston when said rod is oscillated.

14. In a means of the class described, a cylinder, a piston reciprocably mounted in the cylinder, a rod connected to the piston and extending from the cylinder, a release valve in the piston, pump means in the piston for forcing fluid from the chamber at one end of the piston to the chamber at the other end to move the piston, said pump comprising an intake valve at the rear end of the piston, a compression valve at the forward end of the piston, and a plunger in the piston for drawing fluid through the intake valve and ejecting the fluid through the compression valve into the forward compression chamber, said rod being provided at the outer end with a means for rotating the same, a plate cam on the rod within the piston for actuating the plunger in the piston when the rod is oscillated.

15. In a means of the class described, a cylinder, a piston positioned therein and movable relative thereto, a release valve in association with one of the former, said valve, when open, connecting the chambers of the cylinder at the opposite ends of the piston, pump means also connecting said chambers for forcing fluid into one of said chambers from the other, a rod for the piston, and cam means in said cylinder in association with the rod for controlling the valve and for actuating the pump.
